UNITED STATES PATENT OFFICE.

JAMES H. MANN, JR., OF ST. PETERSBURG, FLORIDA.

SPURIOUS-COIN SEGREGATOR.

Original application filed February 27, 1924, Serial No. 695,484. Divided and this application filed April 21, 1925. Serial No. 24,804.

This invention relates to devices for detecting and segregating spurious coins and imitation coins and relates more particularly to detecting the differences in diameter and size of spurious tokens or coins and comprises a division of my application for patent for spurious coin segregator, filed February 27, 1924, Serial Number 695,484.

In the accompanying drawings illustrating my invention—

Figure 1 is a perspective view of the casing of my coin control vending machine;

Figure 2 illustrates a rear view of the assembled structure;

Figure 3 is a front view of the fixed wall of the coin chute;

Figure 4 is an interior view of the assembly of the internal detecting and segregating mechanism;

Figure 5 is a front view of the chute closing plate;

Figure 6 is a back view of the slide actuator for the chute opening and closing plate;

Figure 7 is a detail edge view of Figure 4 illustrating the slide and pivoted plate in normal position;

Figure 8 is a view similar to Fig. 7 showing the slide and pivoted plate in open position.

Within a casing 1, preferably vertically arranged and having slots 2 for the reception of a standard coin or token there is inserted a detecting frame 3 having slot chutes 4—4 and with a central passage 5 leading to a chute 6. Within the channels 4—4 there are provided diameter detecting means comprising a deflecting wedge 8 on the plate 10, hereinafter described, adapted to engage a spurious specimen that is thinner than standard so that it will automatically slip out of the chute when the deflecting wedge engages the tilted specimen as the top half of the latter loses touch with the top groove guides 9 of the channel 4. Standard speci-

mens of coins of predetermined denominations would ordinarily be retained in the passage 5 by means of a chute discharger plate 10 coacting to retain them firstly in the channel or chute 4 by virtue of the upper lips 9 of the chute 4 and the lower lips 9' of the plate 10 coacting to guide the coins in their travel along the central passage 5 and therefrom into the chute 6. Nevertheless, with coins that are of sufficiently full diam-

eter it is sometimes found that they tend to stick in the slots in which they are placed. In order to avoid such a tendency teaser slots 11 are provided into which teaser fins 12—12 carried by the plate 13, hereinafter described may be inserted and with an upward movement of the latter the fins engage the lower edge of the specimen and dislodge same from the slot 4 and impel it into a spurious coin return delivery slot to be described later. The fins 12 are carried by a separating embracing plate 13 with wedge-shaped turned-up portions 14—14' fitting over the edges 15 of the frame 3. This is more clearly indicated in Figures 7 and 8 showing the internal assembly of the device.

It will be noted that a lug 16 integral with the slide is arranged to pass through a slot 17 of an actuator bar 18. The latter is better illustrated in Figure 7 of the drawings. The slide 13, covers the back of the frame 3, and imparts a movement to the discharger plate 10 by engagement of the upper inclined edge portions 14, with the projections 19—19 on the plate 10 to give to the latter an outward motion thereby separating the walls of the central passage or chute 5. Such outward action of the plate 10 is made possible by the engagement of the lugs 20 on the plate 10 with slots 20' in the frame 3 of the device acting as a pivot for the lower edge of the pivoted plate 10. Thus as the actuator bar 18 is moved upwardly, it not only causes an expansion of the walls constituting the chute 5 by moving the discharger plate 10 away from the frame 3 but at the same time it also causes teaser fins 12 to dislodge the arrested specimens in the branch chutes 4—4. With the specimen being standard ample time is given for it to traverse the central passage and pass into the segregating chute 6 before the spreading action is much advanced. Furthermore to facilitate a quick dislodgment the plate 10 carries the guide lips 9' lying over the bevelled lower portion of the chute 4.

In operation, therefore, on placing various slugs, coins, token, etc., into the slot 2 of the casing, the diameter detection automatically follows by virtue of the distance separating the lips 9, 9'. Should the diameter prove insufficient the spurious specimen will tilt toward the pivoted plate and by engaging the bevel surfaces of the spear 8 fall

outside of the chute track 4 and be deposited above the bottom of the casing 1 to appear at the opening 41 at the bottom of the casing. Should the diameter be slightly too full such as to tend to bind within the guiding limitations 9, 9' the specimen will remain lodged until the actuator bolt 35 is operated. On pressing the latter upwardly the teaser fingers 12 rise through the teaser slots of the chute 4 tending to press the specimen toward the central chute 5. Later with the upward movement of the slide 13 carrying the teaser fins the lower lips 9' integral with the pivoted plate 10 are moved away permitting the 15 slightly oversized slug or token to fall away between the pivoted plate 10 and the frame 3 to the opening 41. The slide 13 is attached to the actuator bar 18 by engagement of the lug 16 of the slide engaging with a suitable 20 slot 17 of the bar. The return action of the bar is obtained by means of the actuator spring 29 tending to pull the slide and bar toward the bottom of the casing. Thereupon the cam face of the wedge shaped 25 turned-up portions 14' ride over the top of the projections 19-19 on the plate 10 and

force the same toward the frame 3 and into the collapsed position shown in Figure 7.

I claim—

1. In combination with a chute, a pivoted plate for said chute, said chute having a fixed edge engaging means, and a cooperating bevel wall for said chute, said pivoted plate having a bevel edge engaging means overlapping said bevel wall of said chute, 35 and means to disengage the bevel edge of said pivoted plate from the bevel wall of said chute.

2. In combination with a chute, a movable plate for said chute, said chute having a fixed edge engaging means, and a cooperating bevel wall for said chute, said movable plate having a bevel edge engaging means overlapping said bevel wall of said chute, 40 and means to disengage the bevel edge of said movable plate from the bevel wall of said chute by the movement of said movable plate with respect to said chute.

In testimony whereof I have hereunto set my hand.

JAMES H. MANN, JR.
